UNITED STATES PATENT OFFICE.

EDMUND MORRIS, OF MICHIGAN CITY, INDIANA.

DESIGN FOR CANE FABRIC.

SPECIFICATION forming part of Design No. 25,340, dated March 31, 1896.

Application filed December 30, 1895. Serial No. 573,826. Term of patent 14 years.

To all whom it may concern:

Be it known that I, EDMUND MORRIS, a citizen of the United States, residing at Michigan City, in the county of La Porte and State of Indiana, have invented and produced a new and original Design for Cane Fabric, of which the following is a specification, reference being had to the accompanying drawing, forming part hereof, which shows a piece of cane fabric containing my design.

My design consists of a series of rows of four-pointed star-shaped figures arranged alternately with a series of rows of octagonal figures, there being in the body of the fabric a star-shaped figure between each group of four octagonal figures.

The accompanying drawing shows a face view of a cane fabric with my design applied.

The star-shaped figures *x* are arranged in parallel rows, both vertically and horizontally, throughout the body of the fabric, and the octagonal figures *y* are arranged in parallel rows, both horizontally and vertically, throughout

the body of the fabric alternately with the rows of star-shaped figures. There is a star-shaped figure *x* between each group of four octagonal figures *y*. Each of the star-shaped figures *x* is composed of four arms, the outer end of each of which is beveled or inclined. 25

The fabric presents to the eye of an ordinary observer a multiplicity of clearly-defined star-shaped figures and octagonal figures. 30

The leading feature of my design is the alternate arrangement of star-shaped figures and octagonal figures, substantially as hereinbefore described. 35

I claim—

The design for cane fabric, substantially as herein shown and described.

In testimony whereof I have hereunto subscribed my name. 40

EDMUND MORRIS.
